US00D860829S

(12) **United States Design Patent** (10) Patent No.: **US D860,829 S**
(45) Date of Patent: **** Sep. 24, 2019**

(54) **LIVING ENVIRONMENT MONITORING**

(71) Applicant: **BRILLIANT & COMPANY CO., LTD.**, Seoul (KR)

(72) Inventor: **Jungyon Yun**, Seoul (KR)

(73) Assignee: **BRILLIANT & COMPANY CO., LTD.**, Seoul (KR)

(**) Term: **15 Years**

(21) Appl. No.: **35/505,094**

(22) Filed: **Dec. 4, 2017**

(80) **Hague Agreement Data**

Int. Filing Date: **Dec. 4, 2017**

Int. Reg. No.: **DM/098922**

Int. Reg. Date: **Dec. 4, 2017**

Int. Reg. Pub. Date: **Jun. 8, 2018**

(51) **LOC (12) Cl.** **10-04**

(52) **U.S. Cl.**

USPC **D10/53**

(58) **Field of Classification Search**

USPC D10/104.1, 106.1, 106.2, 106.3, 52-53,
D10/101

See application file for complete search history.
